(57) **CLAIM**

The ornamental design for a desk, as shown and described.

DESCRIPTION

FIG. 1 illustrates an isometric top view of the desk, according to an embodiment of the present invention.

FIG. 2 illustrates a top plan view of the desk, according to an embodiment of the present invention.

FIG. 3 illustrates a front elevational view of the desk, according to an embodiment of the present invention; and, FIG. 4 illustrates a right side elevational view of the desk, according to an embodiment of the present invention.

The left side elevational view of the desk is a mirror image of the right side elevational view of FIG. 4.
